[57] CLAIM

The ornamental design for a lazy susan, as shown and described.

DESCRIPTION

FIG. 1 is a perspective view showing the lazy susan of the present invention;

FIG. 2 is a bottom plan view of the lazy susan shown in FIG. 1;

FIG. 3 is a top plan view of the lazy susan shown in FIG. 1; FIG. 4 is a first elevational view showing the rounded end of the lazy susan;

FIG. 5 is a second elevational view showing the flat end of the lazy susan; and,

FIG. 6 is an elevational view of one of the long sides of the lazy susan, the opposite side by the mirror image thereof.
